United States Patent Office.

JOHN E. FINLEY, OF MEMPHIS, TENNESSEE.

Letters Patent No. 77,601, dated May 5, 1868.

IMPROVEMENT IN CHURNS.

The Schedule referred to in these Letters Patent and making part of the same.

Be it known that I, JOHN E. FINLEY, of Memphis, county of Shelby, and State of Tennessee, have invented a new and useful Improvement in Churns; and I do hereby declare that the following is a full, clear, and exact description of the construction and operation of the same, reference being had to the annexed drawings, making a part of this specification, in which—

Figure 1 is a perspective view.
Figure 2 a sectional view.

A, large cog or drive-wheel; B, small cog-wheel fastened to the rod D; C, small cog-wheel fastened to the tube E; J, framework; H H, flanges; G, thimble; I, key; L L, churn; P, lid of churn; K, crank; N N, screws. I construct my churn in the usual tub-form. Upon the lid P, I attach the framework J, which supports the large cog or drive-wheel A with the small cog-wheels B C, rod D, and tube E, flanged wheel H, thimble G, and flanged wheel H.

I pass the rod D through the thimble F, in such a manner that the cog-wheel B will rest upon the top of the framework J, while the cog-wheel is held in position by means of the end of the tube E resting upon the thimble G, which is held in place by means of the key I, which passes through the thimble G and rod D. Upon the tube E, I attach two or more flanges, set at such an angle as to carry the air through the cream upon the thimble G. I also attach two or more flanges for the purpose of carrying the air throughout the cream. These flanges or wheels are made of zinc, wood, or other suitable material.

The object of my invention is to give to the flanged wheels an opposite or counter-revolving motion, which is done by means of the large cog or drive-wheel A, when operated by the crank, K, while the flanged wheels have their flanges set in such an angle as to carry air into every part of the churn, while the rapid counter-motion breaks the globules, thus hastening butter-making.

What I claim as my invention, and desire to secure by Letters Patent, is—

The combination of the flanged wheels H H, thimble G, key I, tube E, rod D, frame J, drive-wheel A, and cog-wheels B C, arranged and operated substantially as described.
